UNITED STATES PATENT OFFICE

93,225

DESIGN FOR A LUBRICATOR

Lloyd A. House, Chicago, Ill., assignor to Victor Lubricator Company, Chicago, Ill., a corporation of Illinois

Application May 21, 1934, Serial No. 51,863

Term of patent 14 years

To all whom it may concern:

Be it known that I, LLOYD A. HOUSE, a citizen of Canada, residing in Chicago, Cook County, Illinois, have invented a new, original, and ornamental Design for a Lubricator, of which the following is a specification, reference being had to the accompanying drawing, forming a part hereof.

Figure 1 of the drawing is a top plan view of the lubricator showing my new design; and Figure 2 is a side elevation of the same.

I claim:

The ornamental design for a lubricator substantially as shown.

LLOYD A. HOUSE.
